ARCH SUPPORTING SHOE

Horace Parker Gould, Boston, Mass.

Application November 18, 1938, Serial No. 241,109

1 Claim. (Cl. 36—71)

My present invention is a novel and improved shoe.

The invention is more particularly directed to a flexible foot-supporting shoe structure.

Heretofore, many attempts have been made to develop the foot-supporting shoes wherein a supporting member, either of leather, canvas, or flexible webbing has been employed, such devices usually being fitted either in the shoe or to the foot of the wearer after the shoe is made, and requiring separate lacings or adjustable securing means. These prior instep supports or ankle brace structures have been developed largely as custom-made orthopedic instrumentalities and required individual foot fitting or special manufacture, not being suitable for mass production or quantity output as standard articles of footwear, and all such prior devices were objectionable because of extra expense, special operations, special adjustments, securing means, and the like.

In my present flexible foot-supporting shoe structure, I have devised an improved flexible supporting member which is automatically adjustable to the wearer and which can be permanently incorporated into the shoe structure during the manufacture of the shoe and is, therefore, suitable for mass and quantity production in a standard form of footwear and for any size or type of shoe.

Being automatic in its yielding support for the instep or arch portion of the foot and imparting a yielding lifting or supporting tension, my improved shoe thus adjusts itself to variations in the foot of the wearer, constituting, in effect, a yielding support both lengthwise and widthwise to which I have given the name of "arch cradle."

A further feature of the present invention consists in the arrangement and construction whereby the yielding arch cradling or supporting member of the elastic material is not in contact with the foot of the wearer, thereby eliminating the objection as well as the distorting effect of many prior ankle brace supports which usually lifted across the entire foot of the wearer in an undesirable pinching action.

In my construction, I arrange the yielding and lifting action of my arch cradle-like member underneath a portion of the insole so that the lifting member first lifts the foot-contacting portion of the insole in a substantially level manner and, thereafter, exerts a yielding hugging action on the upper part only of the instep or ankle portion of the foot of the wearer.

A still further and most important feature con-

sists in my construction whereby the lifting member is permanently incorporated in the shoe and particularly in a welt shoe by the inseam stitches which hold the upper and insole together and which also are utilized to hold the lower edge portion of the yielding supporting member.

Such supporting member is positioned widthwise of the shoe under a part of the insole and thence is brought upwardly and secured to the opposite side of the shoe upper near the top portion.

While I have herein illustrated my improved shoe and process as applied to the welt type of shoe structure, it may be equally advantageously employed in so-called McKay or Littleway types of shoes.

Further features and advantages will be hereinafter more fully pointed out and claimed.

Referring to the drawing illustrating a preferred embodiment of my improved flexible arch-supporting shoe structure,

Fig. 1 is a plan view of the completed shoe;

Fig. 2 is a sectional lengthwise view, and

Fig. 3 is a cross-sectional view on the line 3—3 of Fig. 2.

As shown in the drawing, the shoe illustrated comprises upper material 1, lining 2, insole 3, an outsole 4 and filling material 5, a heel 6 completing the exterior of the shoe, and a sock lining 7 being fitted at the heel portion. The shoe illustrated in the drawing is of the lace shoe type, and in carrying out my present process as herein illustrated, I first prepare the insole 3 by splitting the same rearwardly thru the heel forwardly to approximately the ball of the foot, as best shown in Fig. 2, leaving a lower layer 10 of the insole and an upper flap or layer 12. The lower or main portion of this insole 10, together with the forepart 3 constituting the main insole, is provided with the usual welt sewing rib 15 to which the welt 16 is secured by the usual inseam stitching 20, and the outsole 4 is secured to the welt 16 by the usual outsole stitching 21, as best shown in Fig. 3.

My novel supporting member 25 consists of a flexible or elastic strip of suitable width to extend lengthwise of the shoe for a substantial distance, approximately as shown in Fig. 2, to provide a firm but yielding or cradle-like support for the instep or ankle of the wearer, the material preferably being elastic webbing with a sufficient stretchability to allow the same to yield both lengthwise and widthwise. This member 25 is assembled with the upper materials on a last and

with the member 25 extending underneath the insole flap 12, the upper end of the member 25 being permanently secured to the upper by one or more rows of stitching 26, and the opposite 5 end being assembled on the last with the upper materials in position to be lasted and caught by the inseam stitching 20.

While the shoe is being lasted, my preferred method consists in first lasting or drawing the 10 member 25 to a substantial tension, then securing the same by the removable lasting tacks while the upper materials are lasted and secured, although both may be pulled and lasted and secured simultaneously by the same lasting tacks, 15 if desired. The extending edge portion of the flexible member 25, after the inseaming 20 has been applied, will then be trimmed off with the rest of the upper materials, the filling 5 applied, and the outsole 4 fitted, whereupon the outsole 20 stitching operation is formed whereby the stitching 21 secures the outsole and welt permanently together.

The lasting operations above described are readily accomplished as the flexible member 25 25 can be drawn across the bottom of the last between the insole portions 10 and 12, and the same worked around the edge of the main insole part 10 in the same manner that the upper materials 1 and 2 are worked around and over the edge of 30 the insole and then secured thereto. The lasting operation, pulling the upper materials and the member 25 into lasted position, is of course performed progressively and as the same are secured by tacks, staples, or the like to the main insole 35 portion 10. Thus, even though the principal tension and stretching of the flexible member 25 is exerted at the marginal edge portion during this lasting, as soon as the last is withdrawn the stretch imparted during the lasting to the member 25 will be readily equalized throughout the 40 entire extent of the member 25 from the inseam fastener 20 to the upper fastener 26.

It is also possible to reverse the operation just described and to secure the member 25 during 45 the regular lasting action, putting in staples or the inseam stitching 20 and then after the last is withdrawn secure the upper edge portion of the member 25 to the upper 1 and 2 by the stitching 26, exerting a lifting or slight straining action on the member 25 to lift the insole portion 12 sufficiently and then put in the stitching 26 or secure 50

the same by stapling, eyelets, or other securing means, even the modern types of shoe adhesives being sufficient for this purpose.

Upon withdrawal of the last the inherent tension of the member 25, due to the lasting, will normally act to lift the foot-contacting portion 12 of the insole slightly and thus afford the automatic and yielding flexibility, arch-supporting action to the foot of the wearer when fitted in the shoe.

If desired, the rear portion of the layer 12 may 10 be and preferably is secured by the heel-nailing operation, the heel nails going entirely thru the outsole and both layers to the upper, and being clenched as usual by a heel-clenching plate on the last, whereupon after the last is withdrawn 15 the sock lining 7 may be supplied.

Thus, it will be seen that I have produced a flexible foot-supporting shoe structure without expensive methods or unusual machines, operations, and individual fitting, which structure will 20 be automatically self-fitting to the foot of the wearer and which, being rigidly secured at each end, first lifts the foot-contacting surface of the insole member 12 in a substantially even direction owing to the rigidity and strength of the material of which the insole is made, and thereafter exerts a lifting and hugging action on the upper part of the ankle of the wearer.

Any desired tension can be placed on the elastic member 25 by the simple operation of lasting, 25 pulling this member around the edge of the insole opposite to that of the lifting portion of the member, and thereafter permanently securing the member 25 in such lasted position to which it has been pulled or positioned, by the inseaming operation. The result is an extremely flexible shoe structure suitable for quantity production and with facility and means for automatic foot-lifting 30 and supporting action.

I claim:

A shoe of the kind described, having an insole 35 formed with a slot widthwise thru said insole along the arch portion, a band of elastic material extending thru said slot and having one end secured to the insole and the opposite end secured under tension to the upper materials substantially above the insole, whereby a lifting 40 yielding action is exerted on the foot-contacting part of the insole at the slotted portion.

HORACE PARKER GOULD.
